UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

TIME-LIMIT CONTROLLING DEVICE FOR ELECTRIC SWITCHES.

1,237,240.

Specification of Letters Patent. Patented Aug. 14, 1917.

Application filed December 23, 1912. Serial No. 738,161.

To all whom it may concern:

Be it known that I, GEORGE A. BURNHAM, a citizen of the United States, residing at Saugus, in the county of Essex and State 5 of Massachusetts, have invented an Improvement in Time-Limit Controlling Devices for Electric Switches, of which the following is a specification.

This invention relates to selective time-limit 10 controlling devices for electric-switches, and is intended as an improvement upon the selective time-limit controlling-device of Patent #1,041,716, dated October 15, 1912. In said patent an electric-motor, responsive to 15 an overload, is employed for moving the switch-operating device into engagement with its actuator and subsequently for driving said actuator to cause the switch operating-device to operate the switch. There are 20 movable means connected with the motor for controlling the engagement of the switch-operating device with its actuator, whereby the switch-operating device is held disengaged from its actuator on an overload 25 of lesser value than that which is designed to move it, permitting engagement of said operating-device with its actuator to be effected by an overload of at least a given value or in excess of such value. There are 30 also means connected with the motor for controlling the starting thereof, whereby it will be held at rest on an overload of a lesser value than that which is designed to start and operate it. The movable means for 35 controlling the engagement of the switch-operating device with its actuator is shown in said patent as a movable part of the field-frame, or a movable part which is arranged in the magnetic-field of the motor, said movable 40 part adapted to be moved in one direction by the attractive influence of said field to cause the switch operating-device to engage its actuator and a spring is connected with said movable part for moving it in the 45 other direction, said spring being adjusted to hold said part against the attractive influence of the magnetic-field upon an overload of lesser value than that which is designed to overcome its force. The means 50 which is connected with the motor for controlling the starting thereof, consists of a brake for the armature, and said brake is connected with said movable means, whereby it is held in engagement with the armature 55 upon an overload of lesser value than that

which is designed to start and operate the motor, but is moved to disengage the armature on an overload of a given value or in excess of such value.

A brake for engaging the armature to hold it at rest and thereby control the starting of the motor, is objectionable for the reason that it is not as positive as is sometimes desired; and another object of this invention is the provision of other means for controlling the starting of the motor, which is responsive to an overload current, and furthermore is or may be adjustable to start and operate the motor on-overloads of different values or in excess of such values. 60 65 70

Figure 1 is a side elevation of a time-limit controlling-device embodying this invention.

Fig. 2 is an end view of the same.

Fig. 3 is a diagram of the circuits.

The novel features embodying my present 75 invention are here illustrated in connection with a time-limit controlling-device such as shown in said patent, but they may be arranged in connection with other forms of time-limit controlling-devices involving the 80 employment of a motor of any form in which motive power is derived from electric currents by means of electro-magnetic action.

Referring to the drawings, the switch-operating-device comprising a yoke or arm 40, with a cross-piece 41 for engagement with a circuit-closing member 27, a shaft 42 upon which said arm is loosely mounted, worm-wheel 43 arranged on said shaft, and 90 screw 44 for detachably connecting said arm with the worm-wheel; a movable part or member 51 of the field-frame of an electric-motor, pivoted at 52, and bearing said switch-operating device; a worm 49 into 95 and out of engagement with which said worm-wheel is movable, which is arranged on the shaft of the armature of said motor, are all as shown in the patent referred to.

Herein the field-coils 60, which are arranged on the field-frame, or the equivalent exciting-coils of the motor, have connected with them numerous branch wires 61, which lead to a corresponding number of stationary switch-plates 62, arranged adjacent a 105 switch-plate 63, which is common to all said switch-plates 62, and sockets are provided between said switch-plates 62, and the switch-plate 63, to receive a switch-plug 64, or equivalent conducting member, thereby to 110

electrically connect the switch-plate 63 with any one of the switch-plates 62 for the purpose of including more or less of the exciting-coils in the circuit. A transformer-circuit 70, or equivalent circuit arranged to be affected by the overload, is connected with the switch-plate 63 and with the exciting-coils, as represented in the diagram Fig. 3, or otherwise, whereby the results herein described may be attained.

By means of the electrical connections and circuits here shown the magnetic-field of the motor will be variable, according to the portion or number of exciting-coils included in the transformer-circuit, and the movable part or member 51 of the field-frame will be caused to respond to any amperage of current for which the device may be set, thus widely increasing the range of adjustment, as contrasted with the employment of a spring, as shown in the patent referred to. As the movable part or member 51 responds the switch operating-device will be moved into engagement with its actuator, but it will be noted that such part or member will not be moved until the magnetic-field is at least of a given strength, due to an overload of at least a given value.

The electric motor here shown is of the repulsion type adapted for operation when its armature is short circuited and herein the armature winding of the motor is arranged in a circuit 85, which is adapted to be opened and closed by a movable switch-member 86, engaging stationary switch-members which are connected with the circuit 85, for the purpose of starting the motor. In order that said movable switch-member may be responsive to an overload it is here shown as connected with the movable part 51 of the field-frame, or other movable means which may be employed in lieu thereof, so that when said part or equivalent movable means is moved in response to an overload of a given value or amperage, or of a greater value or amperage, said switch-member will be moved and the circuit 85 of the armature closed, thereby starting the motor. Hence the starting of the motor and also the operation thereof is controlled by an overload, and furthermore by an overload of at least a given value which may be predetermined, and adjustment made to provide for it. This means of starting the motor is of advantage even though a spring is connected with the movable means for controlling its movement, as in the patent referred to.

I desire to include particularly within the spirit and scope of my invention the adjustable means herein set forth for controlling the operation of the motor on overloads of different predetermined values or in excess of such values, as a motor so controlled is of advantage in connection with a time-limit

controlling-device for the reason that it obviates the necessity of providing overload relays to control the circuit of the motor and also adapts the device to a wide range of adjustment for different predetermined overloads.

If desired, an endless band of copper, shown at 90, may surround a portion of the end of the pole or part 51. This continuous conducting band or ring forms an isolated closed circuit which is so arranged in the magnetic-circuit that a current of a phase relation different from that of the field-coils may traverse the closed circuit and cause said part 51 to remain in attracted position. In said patent the operating-device for the switch is designed to be moved through a definite interval of space to operate the switch, according to the setting, and for the accomplishment of this result the worm-wheel is provided with a series of holes to receive a screw connected with the yoke or frame, and the pin 46 is arranged on the worm-wheel which engages the stop on the frame for determining the normal position or starting point. For ordinary purposes this adjustment is sufficient but in some instances a finer adjustment is required, and to provide for a finer adjustment in a simple manner an adjusting-screw 95 is arranged in the frame, as a stop, for engagement with the pin 46, thereby to determine the normal position or starting point of the movable switch-operating member.

I do not desire to limit my invention to the particular construction here shown, as it is obvious that the same may be modified in many respects yet enable the results here shown to be attained, which come within the spirit and scope of this invention.

I claim:

1. In a time-limit switch controller, a switch-closing member arranged to close a switch when actuated a predetermined distance, having an engaging portion adapted to engage the rotary portion of a motor, a switch adapted to close an electric circuit derived from the circuit to be controlled to actuate the motor, a rotary electric motor having a portion adapted to be moved by electromagnetic attraction of its parts on the occurrence of a predetermined overload on the circuit to be controlled and cause said switch closing mechanism to be connected with the rotating portion of said motor and also close the switch which controls the actuation of the motor.

2. A time-limit device for electric-switches consisting of a switch-operating device, an actuator therefor into and out of engagement with which said operating device is movable, an electric-motor for controlling said actuator, which is responsive to an overload current, and means associated

with said motor, and responsive to an overload current, which is arranged to start said motor and also to move said operating-device into engagement with its actuator upon 5 an overload of at least a given value, substantially as described.

3. A time-limit device for electric-switches consisting of a switch-operating-device, an actuator therefor, into and out of 10 engagement with which said operating-device is movable, an electric-motor for controlling said actuator which is responsive to an overload current, means associated with 15 said motor and responsive to an overload current, which is arranged to start said motor and also to move said operating-device into engagement with its actuator upon an overload of at least a given value, and means arranged to vary the value of the overload 20 to which said starting and moving-means is responsive, substantially as described.

4. A time-limit device for electric-switches consisting of an operating-device requiring a prolonged period of time to 25 operate the switch, an actuator therefor, an electric-motor for controlling said actuator which is responsive to an overload current, a controlling-switch for the circuit of the armature of said motor, and means responsive 30 to an overload current arranged to control the engagement of said operating-device with its actuator and also to operate said controlling-switch to close its circuit upon an overload of at least a given value, 35 and which permits of disengagement of said operating-device from its actuator and the return of said switch to normal when the overload ceases, substantially as described.

5. A time-limit device for electric-switches consisting of an operating-device requiring a prolonged period of time to operate the switch, an actuator therefor, an electric-motor for driving said actuator which is responsive to an overload current, 40 a controlling-switch for the circuit of the armature of said motor, and movable means bearing the movable member of said controlling-switch, which is arranged in the magnetic-field of the motor and adapted to 45 be moved by the attractive influence of said field to close said controlling-switch and thereby start the motor, substantially as described.

6. A time-limit device for electric-switches consisting of an operating-device requiring a prolonged period of time to operate the switch, an actuator therefor, an electric-motor for driving said actuator which is responsive to an overload current, 55 a controlling-switch for the circuit of the armature of said motor, a movable part of the field-frame of said motor bearing the movable member of said controlling-switch, said movable part adapted to be moved by 60 the attractive influence of the field to close 65

said controlling-switch and start the motor, substantially as described.

7. A time-limit device for electric-switches consisting of an operating-device requiring a prolonged period of time to operate the switch, an actuator therefor, into and out of engagement with which said operating-device is movable, an electric-motor for driving said actuator which is responsive to an overload current, a controlling-switch for the circuit of the armature of said motor, a movable part of the field-frame of said motor bearing the movable member of said controlling-switch and also controlling the engagement of said operating-device with its actuator, said movable part adapted to be moved by the attractive influence of the field upon the occurrence of an overload to close said controlling-switch and start the motor and also move said operating-device into engagement with its actuator, substantially as described.

8. A time limit device for electric-switches consisting of an operating-device requiring a prolonged period of time to operate the switch, an actuator therefor, into and out of engagement with which said operating-device is movable, an electric-motor for driving said actuator which is responsive to an overload current, a controlling-switch for the circuit of the armature of said motor, a movable part of the field-frame of said motor bearing the movable member of said controlling-switch, and also controlling the engagement of said operating-device with its actuator, said movable part adapted to be moved by the attractive influence of the field upon the occurrence of an overload to close said controlling-switch and start the motor and also move said operating-device into engagement with its actuator, and means arranged to vary the value of the overload to which said movable part of the field-frame is responsive, substantially as described.

9. A time-limit device for electric-switches consisting of a switch-operating device, an actuator therefor, an electric-motor for controlling said actuator, the exciting-coils of which are included in a circuit responsive to an overload, and the armature of which has its windings arranged in a circuit inductively related to the aforesaid circuit, and means controlled by said exciting-coils and responsive to an overload of at least a given value to close the circuit of said armature, thereby to start said motor only upon the occurrence of an overload of at least a given value, substantially as described.

10. A time-limit device for electric-switches consisting of a switch-operating device, an actuator therefor, into and out of engagement with which said operating-device is movable, an electric-motor for controlling said actuator, the exciting-coils of

- which are included in a circuit responsive to an overload current, and the armature of which has its windings arranged in a circuit inductively related to the aforesaid circuit, 5 and means controlled by said exciting-coils and responsive to an overload of at least a given value, to close the circuit of said armature and to move the operating-device into engagement with its actuator, thereby to 10 start the motor and also effect engagement for the operating-device with its actuator only upon the occurrence of an overload of at least a given value, substantially as described.
- 15 11. A time-limit device for electric switches consisting of a switch-operating device, an actuator therefor, into and out of engagement with which said operating-device is movable, an electric-motor for controlling 20 said actuator, the exciting-coils of which are included in a circuit responsive to an overload current, and the armature of which has its windings arranged in a circuit inductively related to the aforesaid circuit, 25 and means controlled by said exciting-coils and responsive to an overload of at least a given value, to close the circuit of said armature and to move the operating-device into engagement with its actuator, thereby to 30 start the motor and also effect engagement for the operating-device with its actuator only upon the occurrence of an overload of at least a given value, and means arranged to vary the value of the overload to which 35 said controlling-means is responsive, substantially as described.
12. A time-limit device for electric switches consisting of an operating-device requiring a prolonged period of time to operate the switch, an actuator therefor, and an electric motor for said actuator, the field-magnets of which are included in a circuit responsive to an overload, and movable means associated with said motor and 45 adapted to control the starting thereof by closing the circuit of the armature when the field-magnets have become magnetized by an overload of at least a given current value, substantially as described.
- 50 13. In a time-limit switch controller, an electric motor having a member arranged to rotate on the occurrence of a predetermined overload, a switch-closing member arranged to close a switch when actuated a 55 predetermined distance having an engaging portion adapted to connect said switch-closing member with the rotary portion of said motor to be actuated thereby, a switch adapted to close a circuit derived from the 60 circuit to be controlled to actuate the motor, a single electromagnetically-operated device arranged to connect said switch-closing member with the rotary portion of said motor and close the switch which controls 65 the actuation of the motor on the occurrence

of a predetermined overload on the circuit to be controlled and disconnect the same when the overload ceases.

14. In a time-limit controlling device for electric circuits, a rotary electric motor having field coils through which current flows from the circuit to be controlled and in proportion to the value thereof, and an armature having the circuit of its windings normally open, but adapted to be closed by a 70 switch, a switch adapted to close the circuit of said armature windings to cause the motor to rotate on the occurrence of a predetermined overload on the main circuit, an actuating device adapted to close a switch 75 controlling the main circuit, normally disengaged from the motor, and a means adapted to be moved by the magnetic effect of the field on the occurrence of a predetermined load on the main circuit to cause said actuating-device to be connected with the rotary portion of said motor to be actuated thereby, to close the switch controlling the main circuit.

15. In a time-limit controlling device for 90 electric circuits, a rotary electric motor having field coils through which current flows from the circuit to be controlled and in proportion to the value thereof, and an armature having the circuit of its windings normally open, but adapted to be closed by a 95 switch, a switch adapted to close the circuit of said armature windings to cause the motor to rotate on the occurrence of a predetermined overload on the main circuit, an actuating device adapted to close a switch controlling the main circuit, normally disengaged from the motor, and a means adapted to be moved by the magnetic effect of the field on the occurrence of a predetermined 100 load on the main circuit to cause said actuating-device to be connected with the rotary portion of said motor to be actuated thereby, to close the switch controlling the main circuit, and to close the controlling switch 110 for the circuit of the armature windings.

16. In a time-limit controlling device for electric circuits, a switch-closing member for the circuit to be controlled, having an engaging portion adapted to engage the rotary 115 portion of an electric motor, an electric motor having a rotary portion arranged to drive the switch-closing member on engagement therewith, windings for the rotary portion of said motor, the circuit of which is 120 normally open at a switch, a switch adapted to close the circuit of said windings, which windings are in inductive relation to the field of the motor, field coils through which current flows from the circuit to be controlled in proportion to the value thereof, a device adapted to be moved by the magnetic effect of the field on the occurrence of a predetermined overload on the main circuit and cause the switch-closing mechanism to be 125 130

connected with the rotary portion of said motor, to be actuated thereby, and also close the circuit of the windings of the armature, so that the motor will be caused to rotate.

- 5 17. A time-limit device for electric switches consisting of a switch operating device, an actuator therefor into and out of engagement with which said operating device is movable, an electric motor for driving 10 said actuator, a controlling switch for said motor, and movable means for the movable member of said switch and said operating device, which means is responsive to

a predetermined overload and upon occurrence of such overload moves said movable member to close the controlling switch to start the motor and moves said operating device into engagement with its actuator.

In testimony whereof, I have signed my name to this specification, in the presence of 20 two subscribing witnesses.
